DANDY ROLL

Peter S. Sinclair and Kenneth C. Gosling, Holyoke, Mass., assignors to The Sinclair Company, Holyoke, Mass., a corporation of Massachusetts

Application October 3, 1934, Serial No. 746,633

15 Claims. (Cl. 92—48)

This invention relates to dandy-rolls employed in paper-making machines.

One of the objects of the invention is to strengthen a dandy-roll by means of the special construction employed herein.

It is not uncommon for a dandy-roll in use to become clogged with material from the paper web and to require cleaning. This is often done with a steam hose with the result that the temperature strains set up thereby cause the skeleton-like structure of the dandy-roll to break apart. These and other strains frequently damage a dandy-roll so much that it becomes valueless for any further practical use.

It is therefore an object of the present invention as already stated to increase the mechanical strength of a dandy-roll in order to resist the strain described in the foregoing paragraph and also other strains of whatever character.

It is also an object of the invention to maintain the maximum drainage compatible with the desired strength, an object always considered desirable in such devices, and even to improve such drainage by the novel construction described herein.

It is furthermore an object of the invention to provide means for producing a soldered joint that can be made quickly and which will be stronger and more durable than the usual soldered joint in such devices.

Another object of the invention is to provide means for permitting a certain amount of expansion in a dandy-roll, such as that due to temperature changes, without the usual corresponding changes in form and resulting mechanical strains. More specifically it is an object of the invention to provide one or more expansion loops which will permit expansion without undue mechanical strain.

These and other objects of the invention will readily appear to those skilled in the art to which it appertains by a consideration of one embodiment thereof described in the following specification and shown in the accompanying drawings in which

Fig. 1 is a side elevation of a dandy-roll partly broken away;

Fig. 2 is an end view thereof showing the head and parts connected therewith;

Fig. 3 is an enlarged sectional view taken on the line 3—3 of Fig. 1;

Fig. 4 is a section taken on the line 4—4 of Fig. 3;

Fig. 5 is an enlarged section taken on the line

5—5 of Fig. 4 showing one of the rods and winding wire;

Fig. 6 is a section showing the parts of Fig. 5 as seen from the right of Fig. 5; and

Fig. 7 is an enlarged view of one of the expansion loops.

Referring to the drawings more in detail the dandy-roll is supported by two short shafts 11 and 12 each carrying a head as indicated by the reference characters 13 and 14 respectively. While this type of construction is shown in the drawings, it is to be understood that the invention may be equally well applied to other types of construction as for example the type of construction which is commonly referred to as the "open end" type of dandy-roll. The main supporting structure of the dandy-roll is the helically wound strip 15 extending from the head 13 at one end of the dandy-roll to the head 14 at the other end of the dandy-roll. This strip is preferably of an elongated cross section as shown in Fig. 4 to provide maximum rigidity and stiffness and at the same time to permit maximum drainage by offering minimum obstruction to the passage of water from the outside of the roll toward the center. This is accomplished by winding the strip on edge thus presenting to the entrance of the water its smallest dimension.

The outer edges of the helix serve to support a plurality of longitudinally extending rods 16 which are also preferably elongated so that they also present to the inflowing water their smallest dimension. The cross-sectional form of the rods 16 is shown in the drawings as somewhat triangular, that is, the portion at the top or nearest the outside circumference of the dandy-roll, indicated at 17, is somewhat smaller than the bottom of the rod, indicated at 18. This form provides less obstruction to the inward flow of water near the outside of the dandy-roll where it is most likely to get clogged up and the necessary size to furnish the requisite strength is spaced a little farther from the outside. The form shown also seems to provide greater rigidity and strength to the complete structure than the same weight of metal of rectangular cross-section. The underside or the bottom is provided with a groove 19 which is primarily of value in soldering the rods 16 to the helix 15. The groove affords an opportunity for the solder to run in between the strip 15 and the rod 16 much more freely than would be likely with two flat surfaces or approximately flat surfaces in contact with each other. The special features of construction just described with respect to the rod 16 are best seen in Fig. 5.

There are also provided a plurality of reinforcing members for giving to the structure still further rigidity and strength. These members may be divided into two groups, an upper set of 5 members and a lower set of members. The reference characters 20, 21, 22, 23, etc. indicate individual members of the lower set and the reference characters 24, 25, 26, 27, etc. indicate individual members of the upper set. These reinforcing members are preferably in the form of cylindrical rods. The helix 15 is provided with notches 28 in its outer edge for the lower set of members 20, 21, 22, 23, etc., deep enough to receive two of the reinforcing members, one on top 10 of the other, as is clearly shown in Fig. 3. It is preferable to have the reinforcing members cross the successive turns of the helix midway between a pair of rods 16, 16. This is shown in Fig. 1 and in Fig. 3. These reinforcing rods are positioned 15 diagonally, that is, they extend in the direction of a helix having a very large pitch. This requires that each reinforcing member cross each successive turn of the helix at least one of the rods 16 further around circumferentially and one 20 rod is usually preferable to more than one. It will thus be seen that the lower set of rods 20, 21, 22, 23, etc. are positioned helically in the direction of a left-hand screw having a very large pitch. The successive members 20, 21, 22, etc. 25 are shown in Fig. 3 and more clearly in Fig. 1 as being spaced apart circumferentially a distance equal to 4 of the rods 16 which gives a symmetrical structure as will more clearly appear hereinafter.

30 35 The successive turns of the helix 15 are also provided with notches 29 for the upper set of reinforcing members 24, 25, 26, 27, etc. which are about half the depth of the notches 28 so as to receive one of the members only. This upper 40 set of reinforcing members is similar to the lower set in that they cross the turns of the helix midway between the rods 16, in that they extend around circumferentially one rod in extending from one turn of the helix to the next, and in that 45 the adjacent members are spaced 4 rods apart circumferentially. The upper rods differ from the lower rods, first, in that they are positioned slightly nearer the circumference so that the two sets of reinforcing members cross each other readily, one above the other, and in that the upper 50 set of reinforcing members extend in the direction of a right-hand screw instead of a left-hand screw. It is desirable that the two sets of reinforcing members cross each other in one of the 55 deep notches 28 provided in the helix as shown, for example, where the lower reinforcing member 21 and the upper reinforcing member 24 cross each other (see Figs. 1 and 3). With such an arrangement the lower and upper reinforcing 60 members cross each other at every other turn of the helix and at the intermediate turns they cross the helix separately. The angular relationship of the mutually reinforcing parts of the structure, a lower reinforcing member 21, an upper 65 reinforcing member 24, and a portion of one turn of the helix 15 is approximately that of an equilateral triangle. The crossing of the lower and upper members at one of the turns of the helix is not conveniently attained in every case all 70 around the circumference due to the fact that the number of rods in different dandy-rolls is different but so far as it is attainable it is preferable.

While the reinforcing members 20 to 27 are shown positioned beneath the rods 16 it has been

found somewhat easier, all things considered, to solder the rods 16 in place first and then cut the proper notches midway between the rods and push the reinforcing members in endwise under the rods and then solder them in place. 5

The structure already described is for providing strength to withstand strains. In order to reduce the amount of expansion, as well as to provide strength, there are preferably provided one or more expansion loops 33. Each of these 10 loops may be a piece of the same material of which the helix is constructed bent into circular form and then each of the ends formed into a reverse bend 35 terminating in an ear 34. The helix 15 is cut near the end of the dandy-roll as 15 shown in Fig. 7 and the two ears 34 are soldered or otherwise secured to the helix 15 at opposite sides of the cut. The resiliency of the expansion loop 33 permits the two ends of the helix 15, as shown in Fig. 7, to move toward and away from 20 each other with very little distortion or bending of the rods 16. The number of these expansion loops may be varied somewhat at the choice of the designer but very satisfactory results have been obtained by using not more than three or 25 four such loops near each end of the roll. We prefer to place the first loop three or four turns of the helix from the end of the dandy-roll, the second loop about three and one-half turns further along, and each additional loop about the 30 same distance from the preceding one. The reverse bend 35 should be a curve and not a sharp corner so that the bending of the loop will be taken up by the whole loop and not be largely concentrated at the point 35. This is one reason 35 why it is difficult to obtain as satisfactory results with a loop formed in the helix itself.

The rest of the construction is very similar to standard dandy-roll construction. The structure as a whole is rotated while notches 30 are cut in 40 the rods 16 onto which is then wound a winding wire 31. This winding wire is preferably rectangular in cross section to facilitate drainage and is provided with rounded edges as best shown in Fig. 6. And finally a fine wire or screen 32 is 45 placed over the winding wire and sewed or otherwise fastened at the seam to complete the finished structure.

In operation, the dandy-roll construction hereinbefore described possesses rigidity, strength, 50 and permanence in wear to a degree which far exceeds any dandy-roll with which the inventor of the present device is familiar. It is to be particularly observed that the position of the reinforcing members, extending both ways, in 55 the direction of a right-hand screw and in the direction of a left-hand screw, in the notches of the helix, provides in itself a considerable degree of rigidity regardless of the solder in holding the parts in the proper position. Thus it is 60 impossible for a turn of the helix to shift longitudinally as the opposite sets of reinforcing members would be either nearer or farther away circumferentially and the corresponding notches 65 being a fixed distance apart would render such longitudinal movement or shifting impossible.

The triangular form of the longitudinal rods increases the strength and rigidity of the device and greatly improves the drainage while the 70 grooves therein both speeds the work of soldering and improves the quality of the finished joint.

While the helix 15 has been described as of an elongated or rectangular cross section the 75

improvements described herein may also be used with a helix of circular cross section.

It is to be understood that the embodiment of the invention set forth in the foregoing description has been selected for purposes of illustration only and various changes may be made herein without departing from the spirit and scope of the invention as defined in the subjoined claims.

10 We claim:

1. In a dandy-roll, a supporting structure in the form of a helically disposed member of a very small pitch and two sets of helically disposed reinforcing members of very large pitch, one set of said helically disposed reinforcing members extending in the direction of a right-hand screw and the other set of said helically disposed reinforcing members extending in the direction of a left-hand screw.

2. In a dandy-roll, a helically wound flat strip, longitudinal rods fastened to the outer edge of said strip, a winding wire around said rods, a wire screen positioned around said winding wire, and members for reinforcing said helically wound strip extending across the outer edges thereof in both diagonal directions.

3. In a dandy-roll, a helically wound flat strip, longitudinal rods fastened to the outer edge of said strip, a winding wire around said rods, a wire screen positioned around said winding wire, a set of helically disposed reinforcing members extending across the outer edges of said helically wound flat strips, the direction of said members being more longitudinal than circumferential, and a second set of helically disposed reinforcing members extending across the edges of said helically wound flat strips, the direction of said members also being more longitudinal than circumferential, one of said sets of helically disposed members being in the direction of a right-hand thread and the other in the direction of a left-hand thread.

4. In a dandy-roll, a supporting structure in the form of a helically disposed flat strip of a small pitch wound on edge, a plurality of longitudinal rods secured to the outer edges of the convolutions of said helix, and two sets of helically disposed reinforcing members of very large pitch, one set of said members extending in the direction of a right-hand thread and the other set of said members extending in the direction of a left-hand thread, the convolutions of said helically disposed strip having two sets of notches in the outer edges thereof staggered in position with respect to said rods for the reception of said reinforcing members, one set of notches being deeper than the other for one set of members and the other set being more shallow for the other set of members, the crossing of the members being at the edges of the strip and in the deeper notches.

5. In a dandy-roll, a supporting structure having a plurality of supporting means extending in a generally circumferential direction, each of said means having the cross-sectional form of a flat strip, and a plurality of elongated longitudinal rods extending transversely of said supporting means with the longer dimensions thereof disposed radially and with the inner edges thereof secured to the outer edges of said supporting means, each of said rods having a shallow groove along the inner edge thereof.

6. In a dandy-roll, a supporting structure in the form of a helically disposed flat strip of a very small pitch wound on edge, and a plurality

of longitudinal rods secured to the outer edges of the convolutions of said helix, each rod having a substantially triangular cross section with a narrow base positioned against the helix and with the opposite apex positioned outwardly from the helix and said cross section having a shallow recess in the base thereof.

7. In a dandy-roll, a supporting structure in the form of a helix, longitudinal rods positioned across the outer edges of the convolutions of the helix and secured thereto, and an expansion loop positioned in said helix near the end thereof.

8. In a dandy-roll, a supporting helical structure formed by winding a flat substantially rectangular strip on edge, said strip being provided with a plurality of expansion loops near each end thereof.

9. In a dandy-roll, a supporting structure in the form of a helix of flat strip wound on edge, a plurality of longitudinal rods extending across the outer edges of the successive helices and secured thereto, the outer edges of said helices having notches provided therein midway between said rods, and two sets of reinforcing rods positioned in said notches and extending from one end of the dandy-roll to the other, one set extending angularly with respect to a line parallel to the axis of the dandy-roll in the direction of a right-hand screw, and the other set extending angularly with respect to a line parallel to the axis of the dandy-roll in the direction of a left-hand screw.

10. In a dandy-roll, a supporting structure in the form of a helix of flat strip wound on edge, a plurality of longitudinal rods extending across the outer edges of the successive helices and secured thereto, the outer edges of said helices having notches for reinforcing members provided therein, a pair of reinforcing members one positioned above the other in said notches, one of said members extending angularly with respect to a line parallel to the axis of said dandy-roll in the direction of a right-hand screw, and the other of said members extending angularly with respect to a line parallel to the axis of said dandy-roll in the direction of a left-hand screw, whereby said helix is held at the point of crossing of said members from movement longitudinally of said dandy-roll in either direction.

11. In a dandy-roll, a supporting structure in the form of a helically disposed flat strip of a very small pitch wound on edge, each turn of said helix having a plurality of notches spaced circumferentially around the outer edge thereof, and two sets of reinforcing members positioned in said notches, each member of one set extending in one diagonal direction from a notch in one of said turns to a notch in the adjacent turn, and each member of the other set extending in the other diagonal direction from a notch in one of said turns to a notch in the adjacent turn, the members of one set crossing the members of the other set in the notches in the helix.

12. In a dandy-roll, a supporting structure in the form of a helically disposed flat strip wound on edge, each turn having a plurality of notches circumferentially spaced in the outer edges thereof, and reinforcing means positioned in said notches comprising a pair of crossed members extending to the adjacent turns of the helix on both sides of said notch.

13. In a dandy-roll, a supporting structure in the form of a helically disposed flat strip wound on edge, a plurality of longitudinal rods extending across the outer edges of the turns of said

helix and secured thereto, said turns having a plurality of notches in the outer edges thereof positioned midway of said rods, a set of diagonally disposed reinforcing members positioned in 5 said notches and extending from one end of the dandy-roll to the other, and a second set of diagonally disposed reinforcing members positioned in said notches and also extending from one end of the dandy-roll to the other, the two 10 sets of reinforcing members extending in opposite diagonal directions, substantially all of the crossings of members of one set with members of the other set being in notches of the helix.

14. In a dandy-roll, a supporting structure in 15 the form of a helically disposed flat strip wound on edge, a plurality of longitudinal rods extending across the outer edges of the turns of said helix and secured thereto, said turns having a plurality of notches in the outer edges thereof 20 positioned midway of said rods, a set of diagonally disposed reinforcing members positioned in said notches and extending from one end of the dandy-roll to the other, and a second set of diagonally disposed reinforcing members positioned in 25 said notches and also extending from

one end of the dandy-roll to the other, the two sets of reinforcing members extending in opposite diagonal directions and crossing the turns of the helix at the same point in substantially a minimum of fifty percent of the crossings. 5

15. In a dandy-roll, a supporting helical structure formed by winding a flat substantially rectangular strip on edge, a plurality of longitudinal rods extending across the outer edges of the successive helices and secured thereto, the outer edges of said helices having notches provided therein midway between said rods, and two sets of reinforcing rods positioned in said notches and extending from one end of the dandy-roll to the other, one set extending angularly with respect to a line parallel to the axis of the dandy-roll in the direction of a right-hand screw, and the other set extending angularly with respect to a line parallel to the axis of the dandy-roll in the 15 direction of a left-hand screw, said helical strip being provided with expansion loops near each end thereof. 20

PETER S. SINCLAIR.

KENNETH C. GOSLING.
